DESIGN FOR A GRILLE

Louis A. Macklanburg, Oklahoma City, Okla.

Application January 23, 1939, Serial No. 83,148

Term of patent 14 years

To all whom it may concern:

Be it known that I, Louis A. Macklanburg, a citizen of the United States, residing at Oklahoma City, in the county of Oklahoma and State of Oklahoma, have invented a new, original, and ornamental Design for Grilles, of which the following is a specification, reference being had to the accompanying drawing, forming part thereof, and in which:

I claim:

The ornamental design for a grille, as shown.

LOUIS A. MACKLANBURG.
